DRY FREE-FLOWING DETERGENT COMPOSITION
AND METHOD OF PREPARATION

James Cline McKenna, Shaker Heights, Kurt Albrecht, Painesville, and John H. McCracken, Madison, Ohio, assignors to Diamond Alkali Company, Cleveland, Ohio, a corporation of Delaware
No Drawing. Filed Aug. 25, 1961, Ser. No. 133,773
7 Claims. (Cl. 252—135)

This invention relates to detergent compositions and more particularly to detergent compositions having specific applicability as so-called "hard-surface" cleaners, and to the method of preparing such compositions.

Detergent compositions which are applicable for use as "hard-surface" cleaners differ from other types of detergents, particularly those used for textile cleaners. The principal difference of the so-called "hard-surface" cleaners is that they generally contain little or no organic substituents, i.e., materials such as the alkyl aryl sulfonates, which make up a major portion of other detergents, particularly those used for textile cleaning. In contrast, the "hard-surface" type detergent compositions contain alkaline carbonates, phosphates and sometimes silicates, as the principal ingredients thereof. Perhaps the most widely used of such inorganic ingredients are the alkali metal carbonates, such as soda ash, the sesquicarbonates, typically sodium sesquicarbonate, and the alkali metal orthophosphates, typically trisodium orthophosphate. These materials provide water softening characteristics in the composition as well as some detergency. Additionally, these hard-surface cleaning detergent compositions contain various condensed and crystalline phosphates, such as the alkali metal tripolyphosphates, typically sodium tripolyphosphate, and trisodium phosphate, which have good water softening properties. The various pyrophosphates, such as sodium pyrophosphate, are also used, which materials generally have a higher detergency than the tripolyphosphates, although their water softening ability is somewhat less. If desired, these compositions may also contain various silicate materials such as meta- and ortho-silicates, and liquid silicates, as well as anionic, cationic, and non-ionic surfactant materials, which latter materials are generally present in amounts not in excess of about 5% by weight of the total composition.

Heretofore, it has been the practice to form a mechanical mix of the desired phosphates, such as trisodium phosphate and/or sodium tripolyphosphate, and the alkaline carbonate material, such as sodium carbonate. In this dry mix is also included any other materials which may be desired, such as silicates and/or various anionic, cationic, and non-ionic surfactant materials. Although, from the standpoint of cleaning efficiency, such a composition has been found to be satisfactory, the thus-formed dry, mechanical mix is subject to some disadvantages.

The principal disadvantage encountered is, of course, that by means of mechanical mixing it is not possible to obtain a completely homogeneous material. Accordingly, no matter how long the various constituents of the detergent composition are mixed and blended, the composition of the final product is not completely homogeneous. These products, upon vibration and shaking over a period of time, as for example, in transit to either wholesale or retail outlets, undergo a phenomenon known as "layering." In such instances, these is a settling of the heavier particles of material in the composition to the bottom portion of the container while the lighter materials remain in a separate layer in the top portion of the container. Thus, when one goes to use a quantity of this material, which is less than the entire contents of the container, the first amount used will be either more or less alkaline than the last-used. This often results in having a product

which, for some hard-surface cleaning purposes may be too alkaline, thus injuring the surface to be cleaned, while in other instances, has an insufficient alkalinity to clean the surface completely.

5 A further disadvantage in the presently used mechanically mixed hard-surface cleaning detergent compositions is in the various, often expensive, manipulative steps required to provide such a composition. For example, it is necessary that the particle size of both the phosphate material and the sodium carbonate material, as well as that of any other solid materials in the composition, be closely controlled so as to be substantially equal in order that a good mechanical mix can be obtained. This, of course, requires various screening operations with resulting over and undersize particles which must be disposed of in some manner. Additionally, the formation of such a mechanically mixed composition requires numerous mixing or agitation steps in order to effect, at least initially, a uniform dispersion of the various components of the composition. These manipulative steps have been found to be somewhat expensive, both in terms of the equipment required as well as the time which is necessary to carry them out. Notwithstanding the expensive and time-consuming steps which are required, however, 15 the finished product which is obtained is still subject to a degeneration to a non-homogeneous mixture after normal handling.

20 It has now been found that these difficulties, as are presently encountered in the production of a mechanically mixed detergent composition, can be overcome by forming this detergent composition by means of a chemical reaction rather than a mechanical dispersion.

25 It is, therefore, an object of the present invention to provide a detergent composition, particularly one which is applicable to hard-surface cleaning, which composition is not subject to the disadvantages presently encountered in the mechanically mixed compositions.

30 Another object of the present invention is to provide a detergent composition having applicability as a "hard-surface" type cleaner, which composition, when dissolved in water, has substantially the same composition, in terms of Na_2O and P_2O_5 content, as the presently used composition prepared by mechanical mixing.

35 A further object of the present invention is to provide a 40 completely homogeneous hard-surface detergent composition without the expensive and time-consuming screening, grinding, and mixing or agitating steps presently required in forming such compositions.

45 These and other objects will become apparent to those skilled in the art from the description of the invention which follows.

50 In this description and the claims it is to be understood that, in referring to alkali metal compounds, it is intended to include compounds of lithium, sodium, potassium, cesium, and rubidium. Because of their low cost and ready availability the compounds of sodium are preferred, and for this reason primary reference, hereinafter, will be made thereto. This is not to be taken as a limitation, however, but merely as being illustrative of the present invention.

55 The composition of the present invention envisions a detergent composition comprising at least one phosphate of the formula:

60 where M is an alkali metal, x and y are positive integers greater than 0, the sum of which is 3, and a is a number from 0 to 2, at least one alkali metal compound selected from the group consisting of carbonates, bicarbonates, sesquicarbonates, and mixtures thereof, said composition having a mole ratio of $\text{M}_2\text{O}:\text{P}_2\text{O}_5$ greater than about 3:1, and a pH, in a 1% water solution, greater than about 7.5, said composition resulting from a chemical reaction, in

which the reactants are other than the phosphate which is contained in the composition.

In addition to the above materials the detergent composition of the present invention may also contain various optional components, such as silicates and organic surfactant materials. By silicate material is meant the various alkali metal silicates, particularly sodium silicate, including the solid silicates, such as sodium ortho, pyro,

and meta silicates, as well as the various liquid silicate compositions, such as those having an $\text{Na}_2\text{O}:\text{SiO}_2$ ratio within the range of about 1:3.3 to 1:1. In addition to a silicate various organic surfactant materials, either non-ionic, anionic, or cationic, may also be used, which materials may be either in liquid or solid form. Examples of such materials which may be used are found in the following tables:

NON-IONIC SURFACTANTS

Trade Name	Manufacturer	Description
Triton NE	Rohm & Haas Co.	Alkylated aryl polyether alcohol.
Triton X-100	Rohm & Haas Co.	Alkylated aryl polyether alcohol.
Igepal CO-630	General Dyestuff Co.	Alkyl aryl polyethylene glycol ether.
Igepal Ca-630	General Dyestuff Co.	Alkyl aryl polyethylene glycol ether.
Renex 48	Atlas Powder Co.	Polyoxyethylene ester of mixed fatty and resin acids (Tall oil).
Renex 28	Atlas Powder Co.	Polyoxyethylene ester of mixed fatty and resin acids (Tall oil).
Sterox CD	Monsanto Chem. Co.	Polyoxyethylene ether.
Sterox SE	Monsanto Chemical	Polyoxyethylenethio ether.
Sterox SK	Monsanto Chemical	Polyoxyethylol amine condensate.
Alrosol	Alrose Chem. Co.	Fatty alkylol amine condensate.
Alrosol C	Alrose Chem. Co.	Fatty alkylol amine condensate.
Alrosol H	Alrose Chem. Co.	Fatty alkylol amine condensate.
Antarox A-200	Gen. Aniline & Film Co.	Alkyl aryl polyethylene glycol.
Cerfak 1,300	E. F. Houghton & Co.	Alkyl polyoxyethylene alcohol.
Cerfak N-100	E. F. Houghton & Co.	Polyethanolamine fatty acid condensate.
Dergon OM	Arkansas Co.	Amino fatty ester.
Neutronyx 600	Onyx Oil & Chem. Co.	Aromatic polyglycol ether condensate.
Nomic 218	Sharples Chemicals, Inc.	Polyethylene glycol tertdodecyl thioether.
1011	E. F. Drew & Co.	A secondary amide of lauric acid.

ANIONIC SURFACTANTS

Trade Name	Manufacturer	Description
Nacconol F	Natl. Aniline Div. Allied Chem. & Dye Corp.	Modified alkyl aryl sulfonate.
Nacconol NR	Natl. Aniline Div. Allied Chem. & Dye Corp.	Alkyl aryl sulfonate.
Nacconol LAL	Natl. Aniline Div. Allied Chem. & Dye Corp.	Sodium lanol sulfonate.
Santomerse D	Monsanto Chem. Co.	Decyl benzene sodium sulfonate.
Ultrawet 30E	Atlantic Refining Co.	Alkyl benzene sodium sulfonate.
Orvus WA	Procter & Gamble Co.	Sodium salt of lauryl sulfate.
Duponol LS	E. I. du Pont	Technical oleyl sulfate.
Duponol SN	E. I. du Pont	Sodium loral sulfate.
Duponol WAT	E. I. du Pont	Triethanolamine salt of alcohol sulfates.
Aerosol 18	American Cyanamid Co.	N-octyl decylsodium sulfo succinamate.
Airgel	Alrose Chemical Co.	Fatty amide sulfate.
Antaron L-246	General Aniline & Film	Sodium palmitoyl methyltaurate.
Cyclopone A	General Dyestuffs Corp.	$\text{C}_6\text{H}_5\text{CON}(\text{CH}_3)\text{CH}_2\text{SO}_3\text{Na}$.
Igepon T	General Dyestuffs Corp.	$\text{C}_6\text{H}_5\text{CON}(\text{CH}_3)\text{CH}_2\text{SO}_3\text{Na}$.
Lissapol LS	Imperial Chem. Ind.	Sodium oleyl p-anisidine sulfonate.
Michelene D'LC	M. Michel & Co.	Mixture of $\text{CH}_3(\text{CH}_2)_n-\text{C}_6\text{H}_4-\text{SO}_3\text{Na}$ and $\text{CH}_3(\text{CH}_2)_n-\text{CH}_2-\text{C}(=\text{O})-\text{N}-\text{C}_2\text{H}_5\text{OH}$
Miranol HM	Miranol Chem. Co.	Lauroyl imidazolene.
Pactivex	Publicker Ind., Inc.	Sodium dodecyl toluene sulfonate.
Triton W-30	Rohm & Haas Co.	Sodium salt of alkylated aryl polyether sulfate.

CATIONIC SURFACTANTS

Trade Name	Manufacturer	Description
Hyamine 1622	Rohm & Haas Co.	Di-isobutyl phenoxy ethoxy ethyl dimethyl benzyl ammonium chloride.
Onyxide	Onyx Oil & Chem.	Alkenyl dimethyl ethyl ammonium bromide.
Roccal	Winthrop-Stearns, Inc.	Alkyl dimethyl benzyl ammonium chloride.
Alro Amines-C, O-S	Alrose Chem. Co.	
Amine 220	Carbide & Carbon Chem. Corp.	$\text{R}-\text{C}(=\text{N}-\text{CH}_2-\text{CH}_2)-\text{N}-\text{CH}_2\text{CH}_2\text{OH}$
Arquad Series	Armour & Co.	$\text{R}-\text{N}(\text{CH}_3)_3\text{Cl}$; $\text{R}=12-18$ carbon atoms.
Cetab	Rhodes Chem. Co.	Cetyl trimethyl ammonium bromide— $\text{C}_{16}\text{H}_{33}\text{N}(\text{CH}_3)_3\text{Br}$.
Emulsept	Emulsol Corp.	$\text{CH}_3(\text{CH}_2)_n-\text{COOCH}_2\text{CH}_2\text{NHCOCH}_2-\text{N}-\text{C}_2\text{H}_5$
Germ-i-tol	Fine Organics, Inc.	Dimethyl benzyl lauryl ammonium chloride.
Octab	Rhodes Chem. Co.	Octadecyl dimethyl benzyl ammonium chloride— $\text{C}_{18}\text{H}_{37}(\text{CH}_3)_2\text{N}-\text{C}_6\text{H}_5\text{CH}_2$
Oronite Quaternary-ATM50	Oronite Chem. Co.	$\text{N-alkyl benzyl N-N-N trimethyl ammonium chloride}$.
LPC	Hooker Elec. Chem.	Lauryl pyridinium chloride— $\text{C}_6\text{H}_5\text{N}-\text{C}_{12}\text{H}_{25}$

In general, the composition of the present invention is prepared by reacting an alkali metal carbonate-containing material with phosphoric acid, the amounts of these reactants being sufficient to provide a product having a mole ratio of alkali metal oxide to phosphorous pentoxide, e.g., $\text{Na}_2\text{O}:\text{P}_2\text{O}_5$, which is greater than about 3:1. This is preferably done by adding the phosphoric acid to the dry alkali metal carbonate-containing material, typically sodium carbonate, with agitation, in the amount of at least about 1.5 moles of sodium carbonate to 1 mole of H_3PO_4 . The addition of the phosphoric acid to the sodium carbonate is made over a sufficiently long period of time so as to provide complete mixing and reaction of these materials and to prevent the formation of lumps in the reaction mixture. The actual addition time will, of course, depend upon the type of mixing apparatus which is used so that, with more efficient mixing, a shorter addition time can be used. It is to be appreciated that, although lumping in the reaction mixture is not desired, if lumps do occur, the product can still be used by subjecting it to a grinding or crushing operation so as to reduce the lumps to a usable size.

It has not been found that the reaction temperature is extremely critical or that it must be maintained within narrow limits in order to produce the product of the present invention. Thus, it has not been found to be necessary either to heat the reaction mixture or to cool it in order to maintain some desired reaction temperature. It has been found to be preferable, however, that the reaction temperature not exceed about 100° C. for any prolonged period of time during the reaction. When temperatures of this magnitude are maintained over a long period, it has been found that there is an excessive reaction loss, in terms of water and carbon dioxide given off, which loss is desirably avoided, if possible.

The composition produced by this reaction contains at least one phosphate, having the formula:

where M is an alkali metal, x and y are positive integers greater than 0, the sum of which is 3 and a is a number from 0 to 2, and at least one alkali metal compound selected from the group consisting of carbonates, bicarbonates, sesquicarbonates, and mixtures thereof. The phosphate which has been found to predominate in this composition is the di-alkali metal acid phosphate, e.g., Na_2HPO_4 , although the mono-alkali metal acid phosphate, e.g., NaH_2PO_4 , is also formed. These phosphates have been found to be either anhydrous, mono- or di-hydrated, with the di-hydrate appearing to predominate over the mono-hydrate. Thus, the predominant phosphate in the present composition is Na_2HPO_4 , or its dihydrate,

with lesser quantities of the mono sodium phosphate, NaH_2PO_4 or its di-hydrate, $\text{NaH}_2\text{PO}_4 \cdot 2\text{H}_2\text{O}$ being formed. It is to be appreciated, of course, that whether the anhydrous or hydrated form of the phosphate is produced will depend upon the amount of water available in the reaction mixture.

The alkali metal component of the composition of the present invention has been found to be sodium carbonate, sodium sesquicarbonate, sodium bicarbonate, or mixtures of these materials. Inasmuch as the reaction mixture contains an excess of the sodium carbonate in order to provide the necessary $\text{Na}_2\text{O}:\text{P}_2\text{O}_5$ ratio of greater than about 3:1, there would, obviously, be some sodium carbonate in the product, the amount depending upon the initial starting ratio of sodium carbonate to phosphoric acid. Although it is not certain, it is believed that, in the reaction which takes place, carbon dioxide is given off which then reacts with the excess sodium carbonate to form sodium bicarbonate. Where water is also present in the reaction mixture, there will be a further reaction of the sodium bicarbonate with any excess sodium carbonate to form sodi-

um sesquicarbonate or trona. Thus, depending upon the amount of sodium carbonate which is initially used in the reaction mixture, as well as the amount of water present, the final product of the present invention will contain at least one of the alkali metal compounds selected from the carbonates, bicarbonates, and sesquicarbonates and, generally, will contain more than one of these materials, the most likely combination being the carbonate and the sesquicarbonate. It is to be noted, once again, that the product of the present invention is the result of a chemical reaction so that the alkali metal compound will be intimately combined with the phosphates and will not be merely a mechanical mixture.

In the preparation of the composition of the present invention, any type of phosphoric acid may be used. Although the orthophosphoric acid (H_3PO_4) is the most common and least expensive of the phosphoric acids, solutions of the various other phosphoric acids, such as pyrophosphoric acid ($\text{H}_4\text{P}_2\text{O}_7$), tripolyphosphoric acid

and metaphosphoric acid (HPO_3), may also be used. In addition to these, more concentrated phosphoric acids, which are mixtures of the various forms of phosphoric acid, may also be used. Exemplary of such materials is a concentrated phosphoric acid, sold under the name "Phospholeum." This acid has a P_2O_5 content equivalent to 105% H_3PO_4 , and has the following typical analysis:

	Percent
30 Orthophosphoric acid (H_3PO_4)	58
Pyrophosphoric acid ($\text{H}_4\text{P}_2\text{O}_7$)	38
Tripolyphosphoric acid ($\text{H}_5\text{P}_3\text{O}_{10}$)	3.5
Higher polyphosphoric acids, as (HPO_3), e.g., ($\text{H}_6\text{P}_4\text{O}_{13}$), etc.	0.5

35 all of the above being percent by weight of the total composition.

In actual practice the use of this more concentrated phosphoric acid has been found to give definite advantages over the other phosphoric acids, such as orthophosphoric acid. Although the more concentrated phosphoric acid is slightly more expensive than orthophosphoric acid, because of its greater P_2O_5 content, its cost, based on the P_2O_5 content, is about the same as orthophosphoric acid. 40 Additionally, it has been found that, when this more concentrated phosphoric acid is reacted with the soda ash in the method of the present invention, there is substantially no reversion of the pyrophosphoric acid content of the acid to the ortho form. Thus, the product produced contains tetrasodium pyrophosphate ($\text{Na}_4\text{P}_2\text{O}_7$), which material is very desirable in a detergent composition because of its sequestering, dispersing and deflocculating action. Accordingly, by the use of a more concentrated phosphoric acid, which is a mixture of various forms of phosphoric acid, a detergent product is obtained, which contains as a part of the chemical reaction product, a sequestering agent, thus making it unnecessary to add such a material to the composition and combine it by means of mechanical mixing.

60 The concentration of the phosphoric acid used, whether it is a more concentrated mixture of various forms of phosphoric acid or not, has not been found to be extremely critical. Thus, when using orthophosphoric acid, for example, the commercial grade of 85% phosphoric acid may be used. Similarly, various more dilute acids may also be used, such as 65%, 45%, and 25%. Inasmuch as it is desirable that the product, prepared by the present method, is dry and free-flowing, the phosphoric acid concentration should not be so low that excessive 65 quantities must be added to the reaction mixture when the desired P_2O_5 content is obtained. As has been set forth hereinabove the amount of water present in the reaction mix is the principal determining factor as to whether the anhydrous or hydrated forms of the alkali metal phosphates are produced, and also whether the sodium bicar-

bonate produced will combine with the sodium carbonate to produce sodium sesquicarbonate. Inasmuch as any water, present in the reaction mix in excess of that required to perform the above two functions, will tend to make the final product somewhat tacky, thus necessitating an additional drying step, it is preferred that the phosphoric acid used not have a concentration less than about 20% by weight. Again, it will be appreciated, that the choice as to the concentration of the phosphoric acid which is used will be dictated according to the composition which is desired in the final product. Where a detergent composition is required, which contains a hydrated sodium phosphate, or which contains large amounts of trona, the more dilute phosphoric acid will be used. Similarly, where the anhydrous forms of the sodium phosphate are required, or smaller amounts of trona, the converse is true. It is believed that those skilled in the art will be able to determine in each instance the type of composition which is required and, hence, the concentration of phosphoric acid which should be used.

The alkali metal carbonate-containing material, which is reacted with the phosphoric acid to obtain the composition of the present invention, may be the alkali metal carbonate itself, such as sodium carbonate, or it may be a compound containing the alkali metal carbonate, such as sodium sesquicarbonate. Generally, for reasons of cost consideration, it is preferred to use the less expensive alkali metal carbonates, such as sodium carbonate, rather than the more expensive sesquicarbonate. Any of the available forms of the alkali metal carbonate, e.g., sodium carbonate, may be used, including the so-called "light ash" and "dense ash." These materials are, of course, sodium carbonates which differ only in particle structure and bulk density. Additionally, a new and unique form of sodium carbonate, having a granular particle configuration but a low bulk density, may also be used. This material has a bulk density comparable to that of light ash, but, unlike light ash, which is extremely fine, its particle configuration is granular, very similar in size to that of dense ash. In view of the unique characteristics of this material, which characteristics will be referred to in more detail hereinafter, it is the preferred form of sodium carbonate for use in the method of the present invention. For the sake of convenience, this material will henceforth be referred to as granular light ash.

This preferred granular light ash, and its method of preparation, are described in a copending application, Serial No. 119,321, filed June 26, 1961, now Patent No. 3,188,170.

As is set forth in this copending application the granular light soda ash is prepared by mixing a hydrated sodium carbonate with sodium bicarbonate in a proportion of bicarbonate to hydrated carbonate, in terms of alkali metal carbonate equivalents, substantially within the range of 5:1 to 1:2, so as to form substantial amounts of sodium sesquicarbonate in the mixture. Thereafter, the mixture is rapidly heated to a temperature above that at which decomposition of the bicarbonate and sesquicarbonate began, and the carbonate becomes anhydrous. This temperature is maintained for a sufficient period of time to effect decomposition of the mixture while carbon dioxide and water, evolved from the mixture during the heating, are removed. The sodium carbonate product thus produced is then recovered. This product is characterized by larger particles than those obtained by the calcination of an alkali metal bicarbonate alone and a bulk density within the range of about 25 to 45 lbs. per cubic foot. This sodium carbonate product is further characterized by having spheroidal particles of the size such that about 65 to 100% is retained on a 100 mesh screen, and upwards of 92% is retained on a 200 mesh screen.

The use of this granular light ash has been found to be particularly advantageous in forming the present com-

position in that, by its use, a dry granular composition can be formed even when using relatively poor mixing to combine the carbonate material and the phosphoric acid. Additionally, this granular light ash has exceptional absorption characteristics which are particularly advantageous when liquid silicates and organic surfactants are to be included in the subject composition. In this regard it has been found that liquid silicates and non-ionic, cationic, and anionic surfactants can be absorbed by this granular light ash in amounts up to as high as 30% or 35% by weight of the total composition, i.e., the granular light ash plus the silicate or surfactant. Accordingly, where these materials are desired in the present detergent composition, the surfactants can be admixed with the phosphoric acid prior to the time it is added to the granular light ash, and the resulting mixture then combined with the ash. In the case of the silicates they can be added subsequently to the phosphoric acid. In this way, the liquid silicates and/or organic surfactants are absorbed by the granular light ash and the phosphoric acid reacts therewith to form the product of the present invention in dry, granular form, having the silicate and surfactants intimately dispersed therein. Thus, the necessity for any mechanical mixing step is completely eliminated. This granular light ash is further advantageous in view of its rapid solubility in water as compared to conventional light ash and dense ash. For example, comparing the solubility rate of 60 g. of material in 200 ml. of water, the granular light ash dissolves in 22 seconds, while 26 seconds are required for conventional light ash, and 47 seconds for conventional dense ash. It is for these reasons that the granular light ash, as described in U.S. Serial No. 119,321, is the preferred alkali metal carbonate material for forming the detergent composition of the present invention.

As has been set forth hereinabove, the alkali metal carbonate-containing material, preferably the granular light ash, and a phosphoric acid, are combined in amounts which will give a reaction mixture, and hence, a product, having a mole ratio of $\text{Na}_2\text{O}:\text{P}_2\text{O}_5$, which is greater than about 3:1. In order to attain this mole ratio of $\text{Na}_2\text{O}:\text{P}_2\text{O}_5$, it is necessary that the initial reactants are combined in an amount so that the mole ratio of sodium carbonate (Na_2CO_3) to phosphoric acid (H_3PO_4) is greater than about 1.5:1. A preferred ratio of sodium carbonate to phosphoric acid (H_3PO_4) is within the range of about 3:1 to 6:1. Although ratios of sodium carbonate to phosphoric acid, which are greater than 6:1, may be used, the product produced from such ratios has such a high alkalinity that it is not usable for many applications. Accordingly, the preferred upper ratio of sodium carbonate to phosphoric acid (H_3PO_4) is about 6:1, although this is not to be taken as limiting.

It is believed that those skilled in the art will appreciate that, where the lower ratios of sodium carbonate to phosphoric acid are used, there will, obviously, be less excess sodium carbonate in the reaction mixture. Accordingly, this means that less water can be tolerated in the reaction mixture and still obtain a product which is not tacky. In these circumstances, it will be necessary to use the more concentrated phosphoric acids since, as has been set forth hereinabove, additional quantities of water are introduced into the reaction mixture when using the more dilute phosphoric acid. Thus, when using a sodium carbonate to phosphoric acid (H_3PO_4) mole ratio of about 2:1, it is not feasible to use a phosphoric acid having a concentration of less than about 65%, and still obtain a dry, granular product. In contrast, when the mole ratio of sodium carbonate to phosphoric acid (H_3PO_4) used is 6:1, phosphoric acid concentration as low as about 25%, or less, can be used without adversely affecting the free-flowing character-

istics of the product produced. Again, it will be appreciated by those skilled in the art that the mole ratio of sodium carbonate to phosphoric acid, which is used, will depend upon the constituents which are desired in the detergent product. Where, for example, a product is desired having only a small amount of sodium carbonate or sodium sesquicarbonate, the lower mole ratios of sodium carbonate to phosphoric acid, such as 2:1 or 3:1, will be used. Alternatively, where large amounts of sodium carbonate and/or sesquicarbonate are desired in the product, the higher ratios of sodium carbonate to phosphoric acid, such as 5:1 or 6:1, will be used. It is believed that those skilled in the art will readily be able to determine the mole ratio of sodium carbonate to phosphoric acid which is desired, in combination with the concentration of phosphoric acid which is to be used, depending on the constituents which are desired in the finished product.

In order that those skilled in the art may better understand the present invention and the manner in which it may be practiced, the following specific examples are given.

In the following examples the phosphoric acid used is orthophosphoric acid of varying concentrations. The procedure followed consisted in cooling the orthophosphoric acid to 0° C. in a beaker with Dry Ice. The temperature of the sodium carbonate-containing material

5
10
15

When the sodium carbonate material was placed in the blender and the covers sealed, rotation of the blender and the mixing bar was begun. The respective rotational speeds of the blender and mixing bar were 35 r.p.m. and 1700 r.p.m. The phosphoric acid of the desired concentration was fed into the sodium carbonate material through 0.01" openings in the mixing bar. After the phosphoric acid addition was completed, the temperature of the hot product was measured. Mixing of the product was then continued for about 20 minutes so as to provide for partial cooling and absorption of water vapor. The weight of the product was then recorded and the percent weight reaction loss determined.

The amounts of the reactants which were used were determined by the mole ratio of $\text{Na}_2\text{CO}_3:\text{H}_3\text{PO}_4$. For each mole of Na_2CO_3 , 106 g. were used. For each mole of H_3PO_4 , 98 g. were used. Where the phosphoric acid used had a concentration of 85%, 115.3 g. were used for each mole of H_3PO_4 required. Similarly, when using acid concentrations of 65, 45 and 25 percent, the following quantities were used for each mole of H_3PO_4 required:

	G.
65% -----	150.8
45% -----	217.8
25% -----	392.0

Using this procedure, the following runs were made:

used was room temperature, i.e., 24° C. In Examples 1 through 12 the sodium carbonate-containing material was the granular light ash prepared in accordance with the procedure set forth in U.S. Serial No. 119,321. In Examples 13 through 16 the sodium carbonate material used was commercial light ash, having a bulk density of 34.2 lbs. per cu. ft., while Examples 17 and 18 used commercial dense ash, having a bulk density of 61.2 lbs. per cu. ft. The bulk density of the granular light ash used in Examples 1 through 12 was 33.7 lbs. per cu. ft. The sodium carbonate material was placed in a Patterson-Kelley twin shell blender (8 qt. liquids-solids model) just prior to reaction time. This blender is manufactured by the Patterson-Kelley Co., Inc., of East Stroudsburg, Pa. It consists of a V-shape container, provided with covered openings in the end of each leg of the V, through which the material to be blended is charged, and a discharge opening in the apex of the V. The blender is supported by a shaft which passes through both legs of the V about three-fourths of the way up the legs from the apex. The entire blender rotates around this shaft. Additionally, a mixing bar is provided on this shaft, which rotates independently of the blender and through which liquid components are added to the dry materials in the blender.

All of the products obtained in the above examples were dry and free-flowing. Those products obtained in Examples 1 through 12, which used the granular light ash as a starting material, were also granular in form. Similarly, the products obtained in Examples 13, 17 and 18 were also granular in form. The products obtained in Examples 14 through 16 were in the form of a powder. X-ray analysis of all of these products shows that they contain Na_2HPO_4 , Na_2CO_3 , and sodium sesquicarbonate, in varying concentrations depending upon the initial mole ratio of $\text{Na}_2\text{CO}_3:\text{H}_3\text{PO}_4$. Additionally, depending upon the concentration of phosphoric acid used, both the anhydrous and the dihydrated forms of the

were present. It is to be noted that, in the analysis of the product composition, the weight percentages of the Na_2O , P_2O_5 , and CO_2 were obtained by experimental analysis. With regard to the water in the composition the column, headed "Theoretical-as free H_2O " refers to the amount of water which should be present, based upon the water added in the initial reaction mixture. The column, headed "Total H_2O ," is a calculated value arrived at by subtracting the sum of the anhydrous compo-

nents of the mixture, calculated as Na_2HPO_4 , Na_2CO_3 , and NaHCO_3 from 100%. This total amount of water represents the water which is held in the composition as water of hydration for the components, as well as any free water which may be absorbed in the product.

Example 19

By way of comparison an additional run is made, using the procedure as set forth hereinabove with the granular light ash as the sodium carbonate material, and using 85% orthophosphoric acid. The mole ratio of

is 1:1. The phosphoric acid is added over a period of 15 12 minutes, and the final temperature of the product is 95° C. There is a reaction loss in this experiment of 19.2%. The mole ratio of $\text{Na}_2\text{O} : \text{P}_2\text{O}_5$ in the product is 2:1, and the product has the following composition in percent by weight:

Na ₂ O			P ₂ O ₅			CO ₂			H ₂ O	
Theo- retical	Actual	Actual Adj. for Reaction Loss	Theo- retical	Actual	Actual Adj. for Reaction Loss	Theo- retical	Actual	Actual Adj. for Reaction Loss	Theoretical as free H ₂ O	Total
28.0	34.9	28.2	32.1	40.6	32.8	19.9	4.42	3.57	7.8	12.8

The pH of a 1% solution of this product is 7.44, and the product has a bulk density of 48.1 lbs. per cubic foot. Although the product of this reaction is granular in form, it is quite damp and not free-flowing.

By a comparison of this example with the above Examples 1 through 18 it is seen that, when the product has a mole ratio of $\text{Na}_2\text{O} : \text{P}_2\text{O}_5$, which is less than about 3:1, the pH of a water solution of this product is sufficiently non-alkaline as to greatly limit the use of the material. Additionally, it is seen that, unlike the products of Examples 1 through 18, the material produced hereinabove is not free-flowing.

Example 20

An additional experiment is made, using the apparatus and procedure as set forth for the preceding examples. In this experiment the sodium carbonate material is the granular light ash and the phosphoric acid is a concentrated phosphoric acid having the following composition in percent by weight:

	Percent
H_3PO_4	58
$\text{H}_4\text{P}_2\text{O}_7$	38
$\text{H}_5\text{P}_3\text{O}_{10}$	3.5
Polyphosphoric acids as HPO_3	0.5

These materials are reacted in a mole ratio of

of 2:1, to give a product having an $\text{Na}_2\text{O} : \text{P}_2\text{O}_5$ ratio of 4:1. 4,000 g. of the granular light ash are used to which are added 1,762 g. of the concentrated phosphoric acid. The initial temperature of the granular light ash is 24° C. and that of the phosphoric acid is 21° C. The phosphoric acid is added over a period of 26 minutes and the final temperature of the product is 104° C. The reaction loss for this product is 9.79%. The theoretical composition of this product is as follows:

	Percent
Na_2HPO_4	25.70
$\text{Na}_4\text{P}_2\text{O}_7$	17.36
$\text{Na}_5\text{P}_3\text{O}_{10}$	1.53
NaPO_3	0.20
Na_2CO_3	35.19
H_2CO_3	20.02

Experimental analysis of the $\text{Na}_4\text{P}_2\text{O}_7$ content of this product indicates that the actual content of this component is 19.60% before being adjusted for the reaction loss, and is equal to 17.70% after being adjusted for the 5 reaction loss. This value corresponds quite closely to the theoretical amount of 17.36%. The pH of a 1% solution of the product of this example is 9.71, and the bulk density of the product is 41.3 lbs. per cu. ft. as compared to a bulk density of 33.7 lbs. per cu. ft. for the granular light ash. The product obtained is dry, in granular form, and is free-flowing.

From this example it is seen that, when a concentrated phosphoric acid, made up of a mixture of various forms of phosphoric acid, including pyrophosphoric acid, is used in the method of the present invention, there is no reversion of the pyrophosphate in the composition to the orthophosphate form.

Example 21
20 111 g. of a non-ionic surfactant, Triton X-100 (alkyl-

ated aryl polyether alcohol—U.S. Patent 2,504,064) is mixed with 712 ml. of water. To this is added 518 ml. of a 75% H_3PO_4 , and the resulting mixture cooled to about 10° C. Using the procedure and apparatus as set forth for Examples 1 through 18, the phosphoric acid solution is added to 4,000 g. of the granular light ash. The resulting composition was found to be dry and free-flowing, having an Na_2O content of 42% by weight, a P_2O_5 content of 8% by weight, and a non-ionic surfactant content of 2% by weight.

Comparative cleaning tests with this product and commercially available solid and liquid hard surface cleaners showed a decided advantage, in terms of cleaning power for the present composition over the other commercially available compositions tested.

Example 22

The procedure of the preceding example is repeated with the exception that the initial reactant composition consists of 4,000 g. of the granular light ash, 1,540 g. of 50 40% H_3PO_4 , 70 g. of the Triton X-100, and 120 g. of dodecyl benzene sulfonic acid. These materials are reacted, using the procedure and apparatus of the preceding example. The resulting product is found to have an $\text{Na}_2\text{O} : \text{P}_2\text{O}_5$ mole ratio of about 12:1 and is a dry, granular free-flowing composition. Comparative washing tests, using this product and commercially available solid and liquid hard surface cleaners showed that the composition of this example is superior in cleaning power to the other cleaners tested.

From the foregoing, it has been shown that, by the method of the present invention, a detergent composition can be prepared, which composition is at least equal in 60 cleaning power to other commercially available hard surface cleaners. The composition of the present invention has been found to be a granular, free-flowing product, having the various constituents thereof intimately and homogeneously dispersed throughout the composition. The homogeneous characteristics of the present composition are the result of the fact that this composition is obtained by means of a chemical reaction, rather than by mere mechanical mixing.

It is to be understood that, although the invention has been described with specific reference to particular embodiments thereof, it is not to be so limited, since changes

and alterations therein may be made which are within the full intended scope of this invention as defined by the appended claims.

What is claimed is:

1. A dry, free-flowing detergent composition, consisting essentially of a mixture of at least one phosphate of the formula:

where M is an alkali metal, x and y are positive integers greater than 0, the sum of which is 3, and a is a number from 0 to 2, and at least one alkali metal compound selected from the group consisting of carbonates, bicarbonates, sesquicarbonates, and mixtures thereof, said composition having a mole ratio of $M_2O:P_2O_5$ from about 3:1 to about 12:1 and a pH in a 1% water solution, greater than about 7.5, said composition resulting from a chemical reaction between dry solid particles of an alkali metal compound selected from said group and a phosphoric acid, in proportions such as to give said mole ratio, and obtained by intimately dispersing an aqueous phosphoric acid solution in a body of dry solid particles of an alkali metal carbonate with mechanical agitation, while maintaining the temperature of the mixture not substantially in excess of 100° C.

2. A dry, free-flowing, detergent composition, consisting essentially of a mixture of at least one phosphate of the formula:

where x and y are positive integers greater than 0, the sum of which is 3, and a is a number from 0 to 2, with at least one sodium compound selected from the group consisting of carbonates, bicarbonates, sesquicarbonates, and an organic surface-active agent selected from the group consisting of anionic, non-ionic and cationic compounds, said composition having a mole ratio of $Na_2O:P_2O_5$ within the range of about 4:1 to 12:1, and a pH in a 1% water solution greater than about 9.5, said composition resulting from intimately dispersing an aqueous solution of a phosphoric acid and an organic surface-active agent of said group in a body of dry solid particles of said sodium compound so as to effect a chemical reaction between said sodium compound selected from said group and said phosphoric acid, agitating the resulting mixture while maintaining the temperature thereof below about 100° C.

3. A method of preparing a dry, free-flowing detergent composition, which comprises intimately dispersing an aqueous solution of a phosphoric acid in a body of dry solid particles of an alkali metal carbonate selected from the group consisting of carbonates, bicarbonates, sesquicarbonates and mixtures thereof, in proportions such as to give an alkali metal oxide:phosphorus pentoxide ratio from about 3:1 to 12:1, so as to effect a chemical reaction therebetween, agitating the resulting mixture while maintaining said mixture at a temperature not substantially in excess of about 100° C. until the said reaction is complete, and recovering the resulting product characterized by a pH in a 1% water solution, greater than about 7.5.

4. A method of preparing a dry, free-flowing detergent composition, which comprises intimately dispersing an aqueous solution of a phosphoric acid in a body of dry solid particles of a sodium carbonate material in an amount such that the $Na_2CO_3:H_3PO_4$ mole ratio is from 1.5:1 to 6:1, so as to effect a chemical reaction therebetween, agitating the resulting mixture while remaining said

mixture at a temperature not substantially in excess of about 100° C. until the said reaction is complete, and recovering the resulting product characterized by an

5 mole ratio greater than about 3:1 and a pH, in a 1% water solution, greater than about 7.5.

5. The method as claimed in claim 4, wherein the phosphoric acid is a concentrated phosphoric acid containing 10 a mixture of phosphoric acids, including pyrophosphoric acid.

6. A method of preparing a dry, free-flowing detergent composition, which comprises intimately dispersing an aqueous solution of an orthophosphoric acid in a body of 15 dry solid particles of anhydrous sodium carbonate in an amount such that the mole ratio of $Na_2CO_3:H_3PO_4$ is from about 1.5:1 to about 6:1 so as to effect a chemical reaction therebetween, agitating the resulting mixture while maintaining said mixture at a temperature not substantially in excess of about 100° C. until the said reaction is complete, and recovering the resulting product characterized by an $Na_2O:P_2O_5$ mole ratio greater than about 20 3:1 and a pH in a 1% water solution, greater than about 7.5.

25 7. A method of preparing a dry, free-flowing detergent composition which comprises adding an organic surface-active agent selected from the group consisting of anionic, non-ionic, and cationic compounds, to an aqueous solution of orthophosphoric acid, the resulting solution having 30 an H_3PO_4 content of at least about 20% by weight, intimately dispersing the resulting mixture in a body of dry solid particles of sodium carbonate in an amount such that the resulting mixture has an $Na_2CO_3:H_3PO_4$ mole ratio from about 1.5:1 to about 6:1, so as to effect a 35 chemical reaction therebetween, agitating the resulting mixture while maintaining said mixture at a temperature not substantially in excess of about 100° C. until the said reaction is complete, and recovering the resulting product which contains at least one phosphate of the formula:

40 where x and y are positive integers greater than 0, the sum of which is 3, and a is a number from 0 to 2, at least one 45 sodium compound selected from the group consisting of carbonates, bicarbonates, sesquicarbonates, and mixtures thereof, and the organic surface-active agent, said composition being characterized by an $Na_2O:P_2O_5$ mole ratio greater than about 3:1 and a pH, in a 1% water solution, 50 greater than about 7.5.
